(57) **CLAIM**

The ornamental design for an ophthalmic surgery light source adaptor, as shown and described.

DESCRIPTION

FIG. 1 is a perspective view of an ophthalmic surgery light source adaptor design;

FIG. 2 is a right side elevation view of the adaptor of FIG.

1, the left side elevation view being a mirror image thereof;

FIG. 3 is a forward end view of the adaptor of FIG. 1; and, FIG. 4 is a rearward end view of the adaptor of FIG. 1.
